poration of New YorkApplication December 23, 1930
Serial No. 504,244

10 Claims. (Cl. 238—304)

This invention relates to rail anchors and has especial reference to such as prevent the creeping of the rail.

A main object of the present invention is to provide a rail anchor or anti-creeping device of a new and novel construction which is adapted to secure a maximum grip upon the rail and which is simple, inexpensive, positive, easily applied and which acts to restrain rail movement 10 in either direction.

Further and more specific objects, features, and advantages will more clearly appear from the detailed description given below when taken in connection with the accompanying drawing 15 which forms part of the specifications and which illustrates a present preferred form of the invention.

Briefly and generally considered, the invention comprises the ready and simple attachment 20 to the base of the rail of a spring clip or element capable of cooperating with well known types of rail plates and made of spring steel or similar material which firmly grips the base of the rail and yet has sufficient resilient qualities to have a firm grip on any rail to which 25 it may be attached whether that rail is rolled to maximum or minimum base dimensions. Thus the rail anchor element or clip must have sufficient deflective qualities without breaking 30 to suit it to one type of rail or the other. To meet the above requirements it has been found necessary to provide an anchor or clip element which contacts with the rail base at certain 35 particular points only and with these points located in a certain definite relation to each other and preferably spaced a certain maximum distance apart. The clearance of the anchor from the rail base except at specified points and the particular location of the contact points 40 permits it to be deflected slightly for large and small rails without disturbing its ability to firmly grip the rail at the designated points and act properly as an anchor when in use. I contemplate a rail anchor so proportioned and shaped 45 that the greatest part of the grip on the rail base is closest to the lateral edge of the rail base flange. This is secured by applying the leverage principle and spacing the contact points to secure the proper leverage ratio. With 50 the form of rail anchor shown, I secure a tenacious grip on the rail at the lateral edge of the rail base flange nearly in line with the point of resistance on the tie plate and there is no tendency to rotate the rail clip as the rail 55 starts to creep as is the case with the devices

of this kind previously known to the art. The grip on the edge of the rail base flange is secured by a novel disposition of the contact points to secure an increased leverage and the provision of an extended upper portion of said rail 60 gripping member to secure said leverage and to provide the flexibility necessary for adapting said rail base gripping member to rail base flanges of varying dimensions. Preferably the rail rests on a tie plate in which there is disposed an opening or slot into which the lower part of the anchor element lies. The opening and the adjacent face of the anchor element are curved or have angular faces which will cause a jam or wedgelock of the anchor 65 element in the slot or opening in addition to the initial tension or grip of the rail anchor on the rail whenever there is the slightest tendency of the rail to creep along the tie-plate. The cooperation is such that the clip is moved 70 further on to the rail in a wedging manner and in a straight line longitudinal manner, that is to say there is a straight movement of the clip onto the rail and no lateral twisting or swerving 75 from this straight line path.

The drawing which illustrates one present preferred form of the invention is arranged as follows:

Fig. 1 is a cross section through the rail and the tie-plate, taken on the line 1—1 of 85 Fig. 2;

Fig. 2 is a plan view of a short section of the rail and tie-plate adapted to receive the anchor device of the present invention; and,

Fig. 3 is an end elevation of the anchor element;

Fig. 4 is an enlarged side elevation of the rail anchor.

As shown the rail anchor or spring clip element 10 is suitably curved and shaped to be 95 forced onto one of the base flanges 11 of the rail 12. Due to unavoidable variations in the dimensions of the rail flanges or base portions 11, it is necessary to provide an anchor element 10 capable of considerable deflection without failing or breaking, since the element has to be forced on to the rail flange rolled to maximum dimensions without exceeding the elastic limit of the material or setting up too high a stress, and still have sufficient hold or grip on the flange 100 which may be rolled to a minimum dimension. To meet these requirements there is herein provided an anchor element which is so proportioned shaped and curved that on top of the flange 11 there is a definite clearance or space 110

numbered 13 between the points 26 and 27 of the anchor element and the edge of the rail flange 11. The rail anchor 10 contacts with the rail at the points 24, 26, 27 and 28 and is provided with clearance space at 13 and 14 intermediate the points of contact.

The space 13 between contacts points 26 and 27 is provided to permit flexing of the upper element of the anchor between said contact 10 points to facilitate use on rails of different dimensions and to provide leverage to secure a substantial sustained grip on said rail base flange. The contact points 24 and 27 are preferably located close together in order to effect a 15 leverage or increased grip on the rail base flange near its lateral edge as nearly as possible in line with the point of resistance on the tie plate to minimize the tendency of the anchor to rotate or skew around on a vertical axis 20 when the rail tends to creep and the rail anchor becomes jammed between the edge of the rail base flange and the edge of the opening in the tie plate.

The clearances thus provided will permit the 25 sufficient deflection of the clip or anchor element to fit different sized rail flanges without disturbing or affecting the ability of the element to firmly grip the rail flange. Generally speaking it will thus be observed that at its 30 points or ends the clip or anchor element will contact with the upper and lower surfaces of the rail flange 11 and that along its middle portion it will also contact with the flange adjacent its edge.

35 The outer face of the anchor element 10 has angularly disposed surfaces such as 15 and 16 and a lower corner such as 17 which is chamfered to permit its ready insertion and entrance into an opening or slot 18 disposed in the tie-plate 19 beneath the rail 12. This tie-plate and the rail are held to the tie 20 in the usual manner as by spikes 21. The outer faces of the slot or opening 18 are preferably angularly disposed in a manner similar to the faces 15 40 and 16 on the anchor element. Although it is to be understood that these faces of the opening 18 may be curved or otherwise formed but in any event they are preferably of a formation similar to that of the adjacent faces on the anchor element.

In applying the present invention the anchor element is forced on to the rail flange or base 11 by any suitable means such as a sledge or hammer, with the rail in a slightly raised position, after which the rail may be lowered on to the tie-plate 19 and the anchor element 10 guided into the opening 18 assisted by the chamfered corner 17. It is only necessary to force the anchor element far enough onto the flange 11 55 to permit the chamfered corner 17 to enter the opening 18. After entry has been initiated the anchor element will be forced further on to the flange 11 by the driving of the rail spikes 21. The tie-plate 19 is further provided with a longitudinally extending upright shoulder 22 against which the other rail flange 11 bears and against which said flange is forced when the anchor element and the spikes have been properly and finally positioned.

60 As the rail starts to creep, the anchor element 10 which has a grip on the flange 11 is carried between the adjacent edge of the rail flange 11 and the adjacent sloping edge of the opening 18. Since this edge of the opening 18 forms an angle with the lateral edge of the rail flange 11

and the rail anchor element has a corresponding angular curved formation, a wedging action ensues which jams the rail and the anchor element thereon to prevent creeping. The more the rail tends to creep the more jamming action will take place and the tighter will the rail be held. The jamming action takes place when the cam surface moves the clip further on to the rail in a straight line longitudinal manner previously described.

80 As the rail tends to creep the opposite flange 11 is forced tighter and tighter against the shoulder 22 of the tie-plate 19. After the necessary allowed slack of the parts has been taken up, this wedging action locks the rail from further movement. It is apparent that a certain small amount of movement will be initially permitted so that the parts can be readily assembled and disassembled. The offset and locking position of the anchor element when in full 85 effect is approximately indicated by the dotted lines in Fig. 2. The rail anchor element 10 and the surfaces of the opening 18 are sloped and designed to have a similar action to wedge the rail whether the rail moves in one direction or in the opposite direction. Thus the action is a double action.

90 In order to reduce the bending moment on the rail anchor 10 due to the load resulting from the wedging action which has a tendency to break the anchor at any point between the end 24 beneath the rail flange 11 and the lower corner 23 of rail anchor 10, it is preferred to construct the anchor or clip element 10 so as to have a slight angle α on the surface of the anchor as 95 it curves around the edge of the rail flange as shown in Fig. 4. Said surface recedes from the upper edge of the opening 18 in the tie-plate. By having contact between the rail anchor and the tie-plate at the upper edge of the tie-plate 100 at 25, it is obvious that the greater portion of the strain resulting from the wedging action will result in a shear load on the horizontal line at the top surface of the tie-plate rather than a bending moment tending to break the anchor 105 between the inside corner 23 and the end 24.

110 While the invention has been described in detail and with respect to the preferred form shown in the drawing, it is not to be limited to such details and forms since many changes 115 and modifications may be made and the invention embodied in other forms and modifications without departing from the spirit and scope of the invention in its broadest aspects. Hence it is desired to cover any and all forms and modifications which may come within the language or scope of any one or more of the appended claims.

120 What is claimed, is,

1. An anti-creeping device for railway rails 125 which comprises a curved substantially U-shaped strap or clip of spring metal embracing the edge of the base flange of the rail, the strap spaced from the flange except at its ends and near the edge of the flange, a tie-plate on which the rail 140 is disposed, said plate having an opening therein into which opening the clip extends when in place, and means on the clip and the tie-plate for moving the clip on to the rail further in a straight line longitudinal manner perpendicular 145 to the center of the rail when the rail tends to creep in either direction.

2. An anti-creeping device for railway rails which comprises a curved substantially U-shaped strap or clip of spring metal embracing the edge 150

of the base flange of the rail, the strap spaced from the flange except at its ends and near the edge of the flange, a tie-plate on which the rail is disposed, said plate having an opening there-
5 in, into which opening the strap extends when in place, and angularly disposed surfaces on the strap and the opening abutting each other and causing the clip to be jammed onto the rail in a straight line longitudinal manner when the rail tends to creep in either direction.

10 3. An anti-creeping device for railway rails which comprises a clip of spring metal embracing the edge of the rail base flange, a tie-plate having an opening therein in which the clip normally lies, angular faces on the rear of the clip, angular faces on the adjacent face of the opening, said angular faces adapted to co-act to jam the clip onto the rail in a straight line longitudinal manner when the rail starts to creep from normal position in either direction, said clip spaced from the rail except at its ends and near its middle portion, the line of contact of the clip with the tie-plate being near the top of the opening in the tie-plate.

15 4. A rail anchor, comprising in combination, a shouldered tie plate having an opening there thru, said opening having a cam shaped abutting surface, a rail gripping member adapted to grip the rail flange with a substantial sustained spring tension and adapted to abut said cam shaped surface, said spring tension serving to maintain said rail gripping member in locking or jamming relation with said cam shaped abutting surface and tie plate shoulder, said sustained spring tension of said rail gripping member in combination with said jamming or locking relation serving to restrain longitudinal movement of said rail and to move the clip further on to the rail in a straight line longitudinal manner.

20 5. A clip having a wedging action, a clip rail engaging member having a plurality of surfaces adapted to contact a rail flange and maintain said contact regardless of any lateral movement of said clip, a tie-plate having a cam shaped opening, a surface of which engages one portion of the clip on longitudinal movement of the rail and tie-plate, said engagement moving the clip further on to the rail in a straight line longitudinal manner perpendicular to the center of the rail whenever the rail tends to creep in either direction.

25 6. A rail anchor, comprising in combination, a shouldered tie-plate having an opening there thru, said opening having a cam shaped abutting surface, a rail gripping member adapted to grip the rail flange with a substantial sustained spring tension and adapted to abut said cam shaped surface, said spring tension serving to

bring said rail gripping member into locking or jamming relation with said cam shaped abutting surface and tie-plate shoulder, said sustained spring tension of said rail gripping member in combination with said jamming or locking relation serving to restrain longitudinal movement of said rail and to move the clip further on to the rail in a straight line longitudinal manner whenever the rail tends to creep.

30 7. An anti-creeping device for railway rails which comprises in combination, a rail-base-flange-gripping clip having points of contact spaced apart and located to effect an increased leverage grip on said rail base flange near its lateral edge, a tie-plate, said tie-plate having a clip-receiving cam shaped aperture, said clip having a cooperative relationship with said aperture to initiate, increase, and maintain a longitudinal straight line sliding wedging grip between the clip and said flange at all times, whereby the clip is further moved on to the rail in a straight line longitudinal manner perpendicular to the center of the rail whenever the rail tends to creep in either direction.

35 8. An anti-creeping device for railway rails which comprises in combination, an apertured tie-plate, part of said aperture being cam-shaped, a rail base flange-gripping member in said aperture, said cam-shaped portion and said member adapted to co-operate to effect a longitudinal sliding wedge locking of the member on the flange in a straight line manner perpendicular to the center of the rail whenever there tends to be any creeping of the rail with respect to the tie-plate.

40 9. An anti-creeping device for railway rails which comprises in combination a rail base flange gripping member having points of contact located to provide for a substantial range of deflection and to effect a sustained grip on the flange in proximity to its lateral edge, a co-operating tie-plate having an aperture to receive a part of said gripping member, said aperture being formed to effect a longitudinal sliding 115 wedging of the member onto the rail upon a slight movement of the rail in either direction

45 10. An anti-creeping device for railway rails which comprise in combination a tie-plate having an abutting shoulder on one side of the rail base flange and an aperture in proximity to the other side of said rail base flange, a flange gripping member adapted to be received in said aperture and to co-operate therewith to effect a longitudinal sliding wedge lock of the member on the flange to restrain creeping of the rail in either direction.
